SEWING-MACHINE FEED MECHANISM

Richard K. Hohmann, Jamaica, N. Y.

Application April 6, 1948, Serial No. 19,276

2 Claims. (Cl. 112—215)

1

The general object of the present invention is to provide an improved sewing machine work feeding mechanism. More specifically, the object of the invention is to provide improved means for controlling the extent of feeding movement of a sewing machine feed mechanism of the well known type including a feed bar carrying a feed dog and means for moving said feed bar in the work feeding direction with the work engaging portions of the feed dog elevated above the surface of the workbed to thereby advance the work, and for moving the feed dog in the opposite or non-feeding direction with the work engaging portions of the feed dog at a lower level at which they are out of operative engagement with the work.

A specific object of the invention is to provide a simple and effective mechanism for giving the feed dog the customary up and down and horizontal to and fro movements, with improved means for interrupting each work feeding movement of the dog after an extent of feeding movement which may be varied to thereby vary the lengths of the individual stitches formed, made desirable by differences in the character of the work. The feeding movement is indirectly regulated by directly regulating the extent of the non-feeding or return movement given the feed bar. More precisely stated, a specific object of the invention is to provide simple and effective means by which non-feeding, or return, movement may be interrupted at the conclusion of a regulable portion of the full extent of such movement obtainable, without the tendency to shock and noise production which such feeding movement interruption would otherwise tend to create.

In the preferred form of attaining the object of the invention, I make use of an eccentric disc carried by the hook shaft of the sewing machine, and engaging and moving surfaces of the feed bar to give the latter its up and down movements, and to move the feed bar, and thereby the feed dog, longitudinally in the feeding direction against the action of a return or bias spring. The latter gives the feed bar its longitudinal movements in the return or non-feeding direction when the position of the eccentric permits. In accordance with the present invention I provide the feed bar with a slightly yielding or resilient abutment in the form of a strip of spring metal which extends transversely to the length of the feed bar. Each non-feeding or return movement is arrested after the desired extent of such movement, by the engagement of the re-

2

silient abutment carried by the feed bar with a normally stationary abutment adjustably mounted on the sewing machine frame, in position to be engaged by the resilient abutment when the non-feeding movement of the feed bar has attained its desired extent.

10 The various features of novelty which characterize my invention are pointed out with particularity in the claims annexed to and forming a part of this specification. For a better understanding of the invention, however, its advantages, and specific objects attained with its use, reference should be had to the accompanying drawing and descriptive matter in which I have 15 illustrated and described a preferred embodiment of the invention.

Of the drawings:

Fig. 1 is an elevation of the front end of a sewing machine, and

20 Fig. 2 is a perspective view of the feed bar and feed dog.

In the drawings, I have illustrated an embodiment of the present invention in a light weight, portable, chain stitch sewing machine of relatively small size and of the type disclosed 25 and claimed in my co-pending application, Serial No. 19,275 filed of even date herewith. Said machine includes a frame comprising a base A, a standard B and an arm C. Mounted in the front end of the frame arm C is a vertical needle bar D, carrying a sewing machine needle D' at its lower end, and a longitudinally movable presser bar E. The latter carries a presser foot E' at its lower end and is biased for down movement into position in which the presser foot engages the work supported by the workbed portion A' of the sewing machine frame and the hereinafter described feed dog L. Conventional means including a lever F pivoted at the front 30 end of the sewing machine arm, may be provided to raise the presser bar D and thus move the presser foot E' out of operative engagement with the work moving over the workbed A', when this is desirable. A hook G' is carried by a horizontal rotating hook shaft G operatively connected to driving mechanism (not shown), which 35 may be of known form, and operates to rotate the hook shaft and to give work penetrating and loop forming movements to the needle D' in timed relation to the relative movement of the hook shaft as required for the formation of chain stitches.

40 My improved feeding mechanism in the form shown, comprises a feed bar member H operatively associated with the hook shaft G and ex- 45 50 55

tending transversely away from the latter in a generally horizontal direction toward the rear side of the machine. The feed bar is longitudinally movable, and its end adjacent the hook shaft is given up and down movements. The end of the feed bar remote from the hook shaft is in engagement with guiding means carried by the frame base A, and accommodating the longitudinal and the up and down movements of the feed bar. As shown, said guiding means comprises a post or guide pin I having one end anchored to the base A and extending through an open ended, longitudinally extending slot H'. The post or guide pin I is parallel to the workbed surface A' and may well have a threaded inner end screwed into the adjacent end wall of the sewing machine base, and have an enlarged head I' at its front end in engagement with the front side of the feed bar portions at opposite sides of the slot H'. The feed bar is biased for non-feeding movement to the right by a bias spring J mounted in a recess in the feed bar and acting as a compression spring between the shaft I and an abutment shoulder H² of the feed bar. The end of the feed bar H remote from the post or shaft I is bifurcated to form spaced apart upper and lower legs H³, having parallel adjacent sides which straddle a cam or disc K eccentrically mounted on the hook shaft and having a diameter equal to the distance between the parallel feed dog legs H³. The legs H³ are connected by an integral yoke portion of the feed bar, the surface of which is shown as a half cylinder curved about an axis midway between the legs H³ and having a radius length equal to one-half the distance between said legs.

A feed dog L mounted on the feed bar H comprises two elevated, spaced apart, horizontally disposed work engaging bars L'. Each of said bars has a serrated upper edge and is adapted for longitudinal movement in a corresponding slot M' in a plate M which forms an extension of the workbed portion of the frame base A. The slots M' and bars L' are at opposite sides of the path of the needle, as the latter moves downward through a needle hole in the plate M into the position in which the hook G' can engage a loop forming portion of the thread extending between the needle and the work. During the feeding stroke of the feed bar, the work engaging bars L' have their serrated upper edges above the level of the top surface of the work bed, and have lower portions received in said slots and moving longitudinally therein in the direction toward the rear side of the sewing machine. At the end of the working stroke, the cam lowers the adjacent end of the feed bar and thereby lowers the serrated work engaging bars L' in the slots M' so that the upper edges of the bars are below the top surface of the workbed during the longitudinal return or non-feeding movement of the feed bar. Thereafter the serrated bars L' are again raised above the level of the top surface of the workbed preparatory to the next feeding movement of the feed bar.

In accordance with the present invention, the extent of movement of the feed bar in the feeding direction is regulated by the engagement of a resilient abutment member O, secured to the feed bar, with an adjustable abutment member P mounted on the base portion of the sewing machine frame. The abutment member O in the form shown is a thin metal strip extending across the space between the two legs and secured to the latter, with portions in abutting engagement

with the end surfaces of the legs H³. The abutment member P, as shown, is in the form of a lever P connected by a pivot P' to the vertical end wall of the base portion of the sewing machine frame, and having a cam edge P² which is adapted to engage the resilient abutment member O at a horizontal distance to the left of the pivot P' which decreases or increases when the lever P is adjusted about the pivot in the clockwise or counterclockwise direction. The lever P is so mounted as to be frictionally maintained in any adjustment position given it until that adjustment is followed by a different adjustment.

In the operation of the feeding mechanism, when the angular position of the cam K permits, the feed bar H is given a return or non-feeding longitudinal movement toward the cam by the bias spring J. Each such return movement of the feed bar is interrupted when the resilient abutment member O carried by the feed bar, engages the cam portion P² of the abutment lever P. While the longitudinal feeding movements of the feed bar H are quite small, the tension of the spring J must be sufficient to insure the rapid repetition of those movements. In consequence, when each non-feeding longitudinal movement of the feed bar is arrested by the engagement of a rigid portion of the feed bar with a rigid stationary abutment such as is formed by the lever P, there is a tendency to undesirable shock and noise. Such shock and noise is avoided by the use of the resilient abutment member O, and in the practical operation of a sewing machine embodying the present invention, no vibration or tendency of the machine to "creep" or "walk" is apparent.

While in accordance with the provisions of the statutes, I have illustrated and described the best form of embodiment of my invention now known to me, it will be apparent to those skilled in the art that changes may be made in the form of the apparatus disclosed without departing from the spirit of my invention, as set forth in the appended claims, and that in some cases certain features of my invention may be used to advantage without a corresponding use of other features.

Having now described my invention, what I claim as new and desire to secure by Letters Patent, is:

1. The combination in a sewing machine comprising a frame including a base having a workbed portion, and an overhanging arm, and substantially parallel hook and needle bar shafts mounted in said base and arm respectively, of a feed mechanism comprising a cam mounted on said hook shaft, a feed bar elongated in a generally horizontal direction which is transverse to said shaft, guiding means carried by said frame for the end of said feed bar remote from said shaft, the end of the feed bar adjacent said shaft being formed with a bearing surface above and resting on said cam, and with a bearing surface between said remote end and said shaft and facing the latter, means biasing said feed bar for longitudinal movement toward said shaft, a metal strip extending transversely to the length of said feed bar and secured to the end of the latter adjacent said shaft and forming a vertically elongated resilient abutment portion of the feed bar, and an abutment member mounted on said frame at the opposite side of said cam from said guiding means in position to be engaged by said resilient abutment portion and to thereby arrest the movement of the feed bar

toward said shaft and adjustable to vary the extent of longitudinal movement given the feed bar during each feeding operation.

2. The combination in a sewing machine comprising a frame including a base having a work-bed portion, and an overhanging arm, and substantially parallel hook and needle bar shafts mounted in said base and arm, respectively, of a feed mechanism comprising a feed bar extending in a generally horizontal direction transverse to said hook shaft, guiding means carried by said frame for the end of said feed bar remote from said shaft, the end of the feed bar adjacent said shaft being bifurcated to form parallel spaced apart legs and a leg connecting the portion of the feed bar forming a bearing surface facing the hook shaft, a cam mounted on said hook shaft and extending between and engaging the adjacent sides of said legs, means biasing said feed bar for longitudinal movement toward said shaft and thereby tending to maintain said bearing surface in engagement with said cam, a metal

strip extending transversely to said legs across the space between the latter and having its end portions secured to the ends of the legs and forming a resilient abutment portion of the feed bar, and an abutment member mounted on said frame in position to be engaged by said resilient abutment and to arrest the movement of the feed bar toward said shaft, and adjustable to vary the extent of longitudinal movement given the feed bar, during each feeding operation.
